WALTER N. DREW, OF WATERTOWN, MASSACHUSETTS, ASSIGNOR TO ROYAL TYPE-WRITER COMPANY, INC., OF NEW YORK, N. Y., A CORPORATION OF NEW YORK.

CARD-GUIDE FOR TYPE-WRITING MACHINES.

1,219,269.

Specification of Letters Patent. Patented Mar. 13, 1917.

Application filed November 27, 1915. Serial No. 63,761.

To all whom it may concern:

Be it known that I, WALTER N. DREW, a citizen of the United States of America, residing in Watertown, in the county of Middlesex and State of Massachusetts, have invented certain new and useful Improvements in Card-Guides for Type-Writing Machines, of which the following is a specification.

This invention relates to card guides for typewriting machines and has for its object to provide a transparent card and paper guide that will adequately hold cards and paper against the platen in the vicinity of the action of the printing devices or type. The invention belongs to that class of card and paper holders or guides located at the central part of the machine which comprises a guide plate held stationary relative to the transverse traverse of the carriage with its upper edge, which may be provided with a scale, adjacent to and just below the line of print.

Heretofore such guide plates have been provided with upwardly arranged guide devices, as fingers, extending across the line of print and located adjacent the point of print at one or both sides thereof, the arrangement being such that the characters, as printed, are visible and exposed in the printed line for some distance to the left of the printing point.

It often happens in the use of machines having guides of this character that the upper edge or parts of cards, particularly stiff cards, bulge forward above the scale plate and become marked or smeared by the ink ribbon as it moves in front of the operating type and it is to eliminate this objectionable feature in the typewriting of cards, without in any way obstructing the view of the matter being printed, that this transparent card guide and guard has been devised.

The invention is illustrated in the accompanying drawings, in which:

Fig. 1 is a front elevation of that part of a Royal typewriting machine to which this invention is applied.

Fig. 2, a view of the transparent card guide and guard and the scale provided guide plate; and

Fig. 3, a transverse sectional view on line 3, 3, Fig. 1.

4 designates a part of the lower rail of the carriage ball bearing of the shift frame, and 5 the upper rail located at the forward part

of the carriage. The side frames 6 support the rotating platen 7 and below the platen are shown a paper pan 8 and pressure rollers 9 and 10, all of usual construction. In Fig. 1 is shown upper guide rollers 11, ribbon 66 vibrator 12 in lower position and type bar 13 in printing position.

The card guide and guard is held stationary relative to the feeding movements of the carriage and platen, it being secured to the rail 4 of the carriage shift frame by means of the guide supports 14 which are fastened at their lower parts to said rail and extend therefrom forwardly and upwardly in front of the platen to a short distance below the printing line, as indicated in Fig. 3. To the upper ends of the guide supports 14 is secured, by means of screws or screw studs 15, a guide plate 16 that extends a short distance at each side of the printing point with its straight upper edge located just below the line of print, said edge being marked with an indicating scale is shown. The ends of this guide plate are bent or curved forwardly as shown at 17.

The parts so far described are similar to corresponding parts at present in use on the said Royal machine. The gist or essential feature of this invention is in the construction and application of a guide for holding cards, etc., against or toward the platen above the line of print and for fully protecting or guarding the same from interference by any of the moving parts of the machine. To accomplish this object, and at the same time leave the vision free to examine the full line of printing as the characters are impressed on the card or paper between the guide and platen, said guide 18 is composed of a thin sheet or piece of transparent material which may be celluloid or other suitable material. This transparent guide 18 is curved toward the platen, as shown at Fig. 3. In the transparent guide are formed holes 19, Fig. 2, which set over the screws or screw studs 15 of the guide supports whereby it is held in operative position. This transparent guide is provided with a central opening 20 which aligns with an opening in the guide plate 16, as shown at Fig. 2, for the passage of the type when making an impression, as shown at Fig. 1.

It will be observed that the guard 18 is of such size that it extends to a considerable extent on each side of the printing point and

that the two parts of the guide are connected as indicated at 21 above the opening. In this way the guide is made strong and rigid and an unbroken upper edge is provided, thus avoiding the presence of points or angles which might be engaged by the cards. It will also be observed that the guide 18 is secured to the scaled guide 16 and that when the guide 16 is attached to the rail 4 the transparent guide which it carries is properly located.

I claim:

1. A card guide for typewriting machines comprising a fixed horizontally arranged plate having its upper edge disposed below the line of print, and a transparent card guide rigidly attached to said plate having

an unbroken upper edge and formed with an opening through which the type pass to the printing point.

2. A transparent card guide for typewriting machines having side portions disposed on opposite sides of the printing point, a middle portion which rigidly connects said side portions, and an opening for the passage of the type in combination with means for supporting said guide in operative position.

In testimony whereof, I have hereunto subscribed my name.

WALTER N. DREW.
